UNITED STATES PATENT OFFICE.

WELLINGTON PARKER KIDDER, OF JAMAICA PLAIN, MASSACHUSETTS, ASSIGNOR, BY MESNE ASSIGNMENTS, TO ROCHESTER INDUSTRIES, INC., OF ROCHESTER, NEW YORK, A CORPORATION OF NEW YORK.

TYPEWRITER.

Application filed January 11, 1919. Serial No. 270,737.

To all whom it may concern:

Be it known that I, WELLINGTON P. KIDDER, a citizen of the United States, residing at Jamaica Plain, Boston, county of 5 Suffolk, Commonwealth of Massachusetts, have invented certain new and useful Improvements in Typewriters, of which the following is a specification.

This invention relates to typewriting machines and particularly to typewriter shift mechanism.

As illustrative of my invention I have shown a type shift in which the change from upper to lower or middle case is effected through the movement of the main frame of the machine itself. In the form shown in the drawings accompanying this specification I have shown as an illustrative embodiment a folding encased machine having the type shift features above referred to.

While the folding case feature of the machine shown is not itself the subject matter of my present invention, being included in my previous application, Serial Number 264,815, filed November 30, 1918, the collapsibility of the machine does enter into the combination of the type shift principle and should therefore be considered in connection with it.

30 In the drawings:

Fig. 1 is a sectional side view of so much of a typewriting machine in accordance with my invention as is necessary to illustrate the present subject matter with parts 35 in lower case position.

Fig. 2 is a similar view with the parts in middle case position.

Fig. 3 another similar view with the parts 40 in upper case position, and

Fig. 4 a fragmentary plan view of the parts above shown.

The base 1 herein shown is the lower section of a carrying case having the complementary members 2 hinged thereto at 3. 45 One leaf 5 of the hinge is a part of the main support 4 while the other leaf 7 is part of the plate 6 to which the bent link 11 is also pivoted at 13. The support 4 has an upstanding portion 8 to which the bell crank lever 10 is pivoted at 9, its lower end being connected to both the bent link 11 and the slide piece 14 on a common pivot 12. The slide piece 14 is provided with a cam slot 15 which receives one end of the cross

bar X for adjustably supporting the front 55 end of the machine. The upper end of the bell crank 10 receives the cross bar Y for adjustably and collapsibly supporting the platen member of the machine. The hinge and supporting members are in duplicate, 60 one set on each side of the case and detachably receive the machine and support it within its case 1-2.

The foregoing parts designated by numerals are those discussed in my previous 65 application above mentioned and function especially in the collapsing encasement of my machine. They are related, however, to the subject matter of the present application as a phase of the movement of collapse 70 is employed in the shift mechanism which forms the present subject matter.

Referring to only such parts of my machine as are essential to the present invention, the machine proper includes a key frame 75 A having a cross bar B on which keys are pivoted including the shift keys C—C¹. These keys C—C¹ constitute levers which in the form shown rock the key frame A on the cross bar X as a fulcrum to change the position of the type bars (of which one is shown at D) relative to the platen E. Each type bar D has the usual upper, lower and middle case characters indicated as d, d¹, d².

The platen E is mounted in a carriage F 85 transversely sliding on a frame G from which at each side brackets g extend downwardly. In these bracket g are mounted the cross shafts Y and W. The shaft Y is the carrier of the platen member while the 90 ends of the shaft W act as guides in the slot a in the frame A.

The frame G with the carriage F and platen E all collapse within the rear end of the key member A upon the closing of the 95 case 1-2, by the guided movement of the rod ends W—X within the slots a under the actuation of the bell crank 10 the end which is sprung over the end of the bar Y.

The part played by the slot a as far as the 100 present invention is concerned is one of accommodation. It permits the movement of the frame A in shifting the head of the type bars D relative to the platen E to change case. This is accomplished by the shift 105 levers C—C¹.

The lever C pivoted at B has a rearwardly projecting end or support c which

takes under a roller h supported in a bracket H . The bracket H is fastened to the support or base member 1. The tendency of this lever C is therefore to pry the rear end of the key frame A down towards the base 5 tilting it on X and thus shifting the position of the head of any type key D relative to the platen E . It is to be borne in mind that the platen E and carriage F on the support G is independently held during this 10 movement on the bell crank 10 although on account of the shaping of the slot a the travel of the frames A upon the two rods W and Y produces a slight rocking of the entire platen member. This slight rocking preserves the proper position of the platen E relative to the frame A so that the heads of the type bars D will contact with it on the proper line.

20 The potential throw of the lever C is determined at one extremity by the upper end of the slot a and at the other extremity by the stop piece K fixed on the side of the frames A . Pivoted to each one of the side frames A is a lever L fulcrumed at l having a rearward end l' disposed so as to bear on the cross bar Y . The opposite end of the lever L is normally held thrown up by a spring M which is bowed and fastened at 25 m to one of the cross bars of the frame. The tendency therefore of the lever L is to resiliently support the key frame A relative to the platen mount in the position shown in Fig. 1. This, as will be noted from the 30 drawings, leaves the key frame A and the platen mount in a somewhat intermediate position of potential movement, the key frame A being depressible relative to the mount by reason of the upper section of the slot a while the entire platen and its mounting is movable for collapse or erection relative to the key frame A by reason of the 35 lower part of the slot a .

Just below the lower end of the lever L is 40 a stop N pivoted at n and held by a light spring O which normally maintains its upper end in the path of the end of the lever L . The depression of the key C rocks the frame A until the lower end of the lever L contacts with the stop N . This determines the position of middle case as shown in Fig. 2. In order to secure further tilting of the frame A to bring the other line of characters of the type bar D into alinement, the 45 stop N is withdrawn. This is effected by the auxiliary shift key C' which lies closely adjacent to the finger piece of the key C so that both keys may be depressed at once when desired. When so depressed the rear 50 end of the key frame may be rocked to its lowest position and when the rod ends Y are at the ends of the slots a the third type position is assured.

In this manner I am able to secure simple, efficient, but positive shift with mini-

mum of parts and not only without interference with the collapsing feature of my typewriter, but by utilization of the elements of that very feature.

Various modifications may obviously be 70 made in the form and arrangement of parts, and the principles involved may be variously applied in machines other than of the type shown, and all without departing from the spirit of my invention if within 75 the limits of the appended claims.

What I therefore claim and desire to secure by Letters Patent is:

1. In a typewriting machine, a platen frame and a key frame mounted together to 80 be guided relatively in movable relation, a supporting means for said frames comprising a pivotal support for the key frame, and case shift means for rocking said key frame relative to said platen frame.
2. In a typewriting machine, a platen carrier, a support for said carrier, a key and type frame operatively mounted relative thereto, a fulcrum for the frame, and means for rocking said frame relative to said 90 platen carrier for type shift.
3. In a typewriting machine, a platen, a support for said platen, a fulcrumed frame carrying key and type elements, and means to swing said platen and to rock the frame 95 on said fulcrum to change the relative type impact on the platen for type shift.
4. In a typewriting machine of the class described, a base, a collapsible platen support on said base, a platen frame on said support, a key frame movably mounted on said base, said platen support and key frame having relative movement of collapse, and case shift means for producing a movement of said key frame on its support, while said 100 platen support is maintained in its uncollapsed position for type shift.
5. In a typewriting machine of the class described, a base, a platen support on said base, a platen frame on said support, a key 110 frame movably mounted on said base, said platen frame and key frame having relative movement of collapse, and a key shift for producing a movement of said key frame on its support relative to said platen frame for 115 case shift movement.
6. In a typewriting machine of the class described, a base, a fulcrumed collapsible platen frame support thereon, a key frame 120 movably mounted on said base, a platen frame mounted on said support and collapsible relative to said key frame, case shift means for moving said key frame relative to said platen frame and stops for selectively determining said relative movement.
7. In a typewriting machine of the class described, a base, a platen frame support thereon, a platen frame mounted on said support, a key frame movably mounted on 125

- said base and yieldingly supported on said platen support, case shift means for positively moving said key frame relative to said platen support and a movable stop for 5 selectively determining said relative movement.
8. In a typewriting machine of the class described, a support, a platen frame collapsibly mounted on said support and a key 10 frame also collapsibly mounted thereon, and means for selectively moving said key frame independently of said platen frame for type shift relative to said platen.
9. In a typewriting machine of the class 15 described, a base, a platen frame and a key frame mounted for movement relative to each other, key levers mounted in the key frame, type bars carrying a plurality of type, supporting elements for the two 20 frames and movable relatively to said base, and means for moving said frames relatively independent of said support for type shift.
10. In a typewriting machine, a platen frame, a key frame, collapsible supporting elements on which said frames are 25 mounted for relative movement, means for effecting the collapse of said elements to effect said relative movement, and independent means to move one frame relative to the 30 other for type shift and without the collapse of said support.
11. In a typewriting machine, the combination of a case comprising two parts connected for opening and closing movement, a 35 compactible typewriting machine frame including a platen frame and a key and type frame, a connection between the case and said frames for effecting a compacting movement of said frames relative to each 40 other when the case is closed, and independent means for moving said frames relative to the other to effect type shift of the machine.
12. In a typewriting machine, the combination of a case comprising two parts connected for opening and closing movement, and the platen frame and a key and type frame of a compactible typewriting machine, a connection between the case and 45 said frames for effecting a compacting movement of said frames relative to each other when the case is closed, independent means for moving said frames relative to each other to effect type shift of the machine and stops for predetermining the limits of the type shift movement.
13. In a typewriting machine, the combination of a case comprising two parts connected for opening and closing movement, 50 a compactible typewriting machine frame including a platen frame and a key and type frame, a connection between the case and said frames for effecting a compacting movement of said frames relative to each other, and a retirement of the machine
- within one of said parts, and independent means for moving said frames relative to each other to effect type shift of the machine.
14. In a typewriting machine, the combination of a case comprising two parts connected for opening and closing movement, a compactible typewriting machine frame including a platen frame and a key and type frame, a connection between the case and said frames at front and rear for effecting a compacting movement of said frames, and independent means for rocking the platen and key frames on the front connection to effect type shift of the machine. 70
15. In a typewriting machine, the combination of a case comprising two parts connected for opening and closing movement, a platen frame and a key and type frame, a collapsible support for the platen frame, 75 a collapsible support for the key frame, a connection between the case and said supports for effecting a compacting movement of said frames relative to each other, and case shift means for moving said key frame 80 independently of its support to effect type shift.
16. In a typewriting machine, the combination of a case comprising a base and top connected for opening and closing movement, a compactible typewriting machine frame snugly fitting said case and normally substantially in contact with said base, said typewriting machine frame including a platen frame and a key and type frame, connected to each other for relative movement, an elevating device for each of said frames, a connection between the top and said elevating devices to raise said machine frame 90 from the base and means to rock the key 95 frame on the base.
17. In a typewriting machine, the combination of a case comprising a top and a base connected for opening and closing movement, a typewriting machine frame including a depressible key frame substantially in contact with said base when the case is closed, and a connection between the top and the base for effecting a separation of said frames and base to permit the key frame 100 110 depression.
18. Case shift mechanism for folding typewriter comprising a platen carriage bed, a machine frame, means for moving said platen carriage bed relatively to said machine frame to compact the dimensions of the machine for carrying purposes, and case shift mechanism for moving said machine frame relative to the platen carriage in the same path which the parts travel relatively to each other during compacting movement. 115
19. In a folding typewriter machine, a carrying case, a machine frame mounted in said carrying case, type bars pivoted in said 120 125 130

machine frame, a platen carriage bed supported upon said carrying case and guided by said machine frame, and case shift mechanism adapted to cause relative movement between said machine frame and said platen carriage bed to change the elevation of the pivots of the type bar for case shift.

20. In a folding typewriter machine, a supporting bed, a machine frame mounted for movement upon said supporting bed, type bars, and actuating mechanism therefor, carried by said machine frame, a platen carriage bed adapted to be lowered when the machine is folded, a platen mounted upon

said platen carriage bed, means mounted upon said supporting base and being adapted to support said platen carriage bed, and case shift mechanism for causing relative movement between said machine frame and said platen carriage bed to change the position of the pivots of the type bars for the case shift movement. 15

In testimony whereof I affix my signature in presence of two witnesses.

WELLINGTON PARKER KIDDER.
